UNITED STATES PATENT OFFICE.

ADOLPH PEDERSEN, OF CLEVELAND, OHIO, ASSIGNOR TO THE VAN DORN-ELLIOTT ELECTRIC COMPANY, OF CLEVELAND, OHIO, A CORPORATION OF OHIO.

MOTOR-CONTROLLER.

No. 850,872.

Specification of Letters Patent.

Patented April 16, 1907.

Original application filed September 19, 1904, Serial No. 224,953. Divided and this application filed August 16, 1905. Serial No. 274,396.

To all whom it may concern:

Be it known that I, ADOLPH PEDERSEN, a citizen of the United States, and a resident of Cleveland, county of Cuyahoga, and State of Ohio, have invented a new and useful Improvement in Motor-Controllers, of which the following is a specification, the principle of the invention being herein explained and the best mode in which I have contemplated applying that principle, so as to distinguish it from other inventions.

My invention relates to mechanism for controlling the operation of electric motors.

Reference need scarcely be made to the fact that one of the chief difficulties in using an electric motor where a variable load is encountered is to control the current so as to prevent it from becoming excessive and burning out the motor-windings or otherwise damaging the machine. This difficulty is increased when the operative handling the motor is inexperienced or careless.

The object of my invention, then, is to provide a controller for electric motors that will be automatic in its action and withal simple in construction and easily manipulated.

Said invention consists of means herein-after fully described, and specifically set forth in the claims.

The annexed drawings and the following description set forth in detail certain mechanism embodying the invention, such disclosed means constituting but one of various mechanical forms in which the principle of the invention may be used.

In said annexed drawings, Figure 1 represents a plan view of my improved motor-controller in its casing. Fig. 2 represents a horizontal cross-section of the same as cut by a plane passing through line 2 2, Fig. 4. Fig. 3 represents a vertical cross-section thereof as cut by a plane passing through line 3 3, Fig. 4; and Fig. 4 represents a vertical cross-section thereof as cut by a plane passing through line 4 4, Figs. 1 and 2.

The subject-matter of this application has been divided out of my prior application for United States Letters Patent for an improvement in electrically-operated portable drills, Serial No. 224,953, filed September 19, 1904. However, my motor-controller, although originally designed and particularly

suited for use on electrically-operated portable drills because of its simplicity and lightness is equally well adapted for use in numerous other situations where it is desired to provide a small, compact, and efficient controlling mechanism.

In the form of my improved motor-controller shown in the accompanying drawings, A designates the casing within which the controller is contained, and B a handle rotatably attached thereto. In the particular application of the controller to the situation above referred to casing A would either form a part of or be attached to the motor-casing M, Figs. 3 and 4, and handle B would preferably be one of the handles whereby the drill is manipulated. The incased controller, as shown in the figures just referred to, is secured to the motor-casing substantially directly over one of the pole-pieces P of the motor-field. The manner in which handle B is attached to casing A appears in Fig. 4. The inner end of the handle is of reduced diameter to fit in the bore of a boss A', projecting from the casing A, and the portion of the handle extending within the casing is still further reduced, so that an offset b is formed, which rests on a ledge formed within the bore of boss A' and is held against such ledge by means of keys b', fitted in boss A', so as to register in a groove b², encircling handle B.

Secured to handle B, so as to fit over and cover boss A', is a sleeve B', provided with a bottom flange b³, which has formed in its periphery a notch b⁴, Fig. 1, cut upon the arc of a circle. Adjacent to this sleeve B' is the knob C of switch C', Fig. 2, arranged to reverse the current through the motor which it is desired to control. Knob C is provided with a circular bottom flange c, which has a diameter substantially equal to that of the arc of notch b⁴ in flange b³, and has formed in its periphery two notches c' of the same curvature as that of flange b³. A sort of Geneva stop is thus formed, by means of which it is evident that the operation of the reversing-switch C' is prevented except when handle B occupies a certain position, such position being determined by the location of notch b⁴ on flange b³. The object of this arrangement will appear in what follows.

Mounted on the end of the handle B which

projects within casing A are two disks D and E of substantially the form shown in Figs. 2 and 3. Of these two disks disk E is rotatable upon the handle, whereas disk D is attached thereto by means of a lock-nut b^5 , so as to rotate therewith. A washer w serves to separate disk E from the casing A, and a similar washer w' serves to separate the two disks from each other. Disk E is composed of non-conducting material and has mounted upon the edge of its projecting side a segmental contact member E' , which is adapted to contact with one, two, up to all of a series of contacts k , mounted upon an insulating-block K and permanently connected with each other through suitable resistances (not shown) interposed one between each pair of contacts except the first, to which line-wire L of the motor-circuit is connected.

As will be readily understood, the circuit connections are such that by rotating disk E with contact member E' the circuit is first closed, when the first two of contacts k are joined, and the resistances are then successively cut out, so that when such member is in contact with all of contacts k the full current is allowed to pass through the motor.

As has been stated, disk E is rotatable upon handle B, and it is normally held in its "off" position—i. e., so that the circuit is broken—by means of a coil-spring E^2 , which encircles washer w and is attached at one end to casing A and at the other to such disk E. Rotation of disk E from such normal position, so as to connect the circuit and successively cut out the interposed resistances, is effected by rotation of disk D, which is connected with disk E by means of a form of catch. This catch comprises a flat spring d , Figs. 2 and 4, attached to the under side of disk D, and bears on its free end a pin d' , which projects up through an aperture d^2 in such disk far enough to engage an aperture e in disk E when the two disks occupy the proper relative positions. Thus by turning the handle B and disk D attached thereto until pin d' is brought into register with aperture e in disk E such last-named disk becomes also rotatively attached to handle B and can be rotated to turn on the current as desired.

Passing through the motor-casing M and screwed into the pole-piece P, adjacent to the controller, so as to have its upper end lying in proximity to the path of travel of spring d as disk D is rotated, is an iron member P' . Such construction, it will be observed, will render this member P' magnetic when pole-piece P is magnetized by the flow of current through the motor-field. By locating member P' so that pin d' will be directly above it when the disk E has been rotated thereby to its "on" position it is evident that upon the attraction of magnetic member P' becoming sufficiently strong pin

d' will be drawn toward it and disk E be thus released and, under the influence of spring E^2 , be returned to its off position. This will occur whenever the magnetic flux of the motor reaches a certain predetermined amount gaged by the flexibility of spring d .

The mechanism of my improved motor-controller having been thus described in detail, it only remains to indicate its mode of operation. Normally the disk E is in the off position. To turn the current on, handle B, and thereby disk D, must be rotated until pin d' engages aperture e , whereupon disk E also becomes connected with handle B, so as to rotate therewith, and can accordingly be turned to connect the circuit and to successively cut out the resistances placed between contacts k until the full current is flowing through the motor. By turning the handle in the opposite direction one or more of such resistances can be replaced in the circuit. To reverse the current, the handle has to be turned back until the circuit is broken before the notch b^4 in flange b^3 will be positioned to permit the rotation of knob C of reversing-switch C'. Such reversing-switch is securely locked from turning at all other positions of the handle B.

If, while the current is on for any reason such current becomes so strong as to endanger the motor, the member P' simultaneously becomes sufficiently magnetized to attract pin d' to itself, and thus automatically turn the current off in the manner already set forth. It is thus seen that with my controller in use a workman cannot reverse the current through the motor without first turning the current off. Neither can he continue using the motor under conditions that render it liable to be burnt out, for immediately upon such conditions being approximated the current is automatically turned off. At the same time the current is capable of manual control as well so long as such bounds of safety are not overstepped. The simplicity of the device and the protection of its parts from any interference adapt my controller for use in the hands of an inexperienced operator.

I wish particularly to point out that I have provided a very convenient arrangement whereby one of the handles utilized for moving and guiding the drill or other machine is also utilized for operating the controller, although obviously separate handles might be used for these two purposes, that the operative can in no way hold or force the machine to the work over and above its adjusted capacity, and that whereas heretofore separate and independent means, such as a solenoid in the main armature-circuit, have been utilized for operating the safety appliances I accomplish this purpose by means of the magnetic flux of the motor-field.

Having thus described my invention in detail, that which I particularly point out and distinctly claim is—

1. The combination with an electric circuit and a motor therein; of a cut-out switch comprising a movable contact member controlled by the magnetic flux of such motor, and adapted to open the circuit when such flux reaches a predetermined maximum. 5
2. The combination with an electric circuit and a motor therein; of a motor-controller comprising a movable contact member, and manually-operable means adapted to move said member and controlled by the magnetic flux of such motor. 10
3. The combination with an electric circuit and a motor therein; of a cut-out switch comprising a movable contact member; means adapted to retain the same normally in a predetermined position; and means adapted to move said member to and retain the same in any other desired position, said latter means being controlled by the magnetic flux of such motor and adapted to have its operative and inoperative conditions changed from one to the other only when such flux reaches a predetermined maximum. 20
4. The combination of an electric circuit and a motor therein; a cut-out switch comprising a movable contact member; means adapted to retain the latter normally in its "off" position; and means adapted to move said member to and retain the same in any other position, said latter means being controlled by the magnetic flux of such motor, and adapted to be changed from an operative to an inoperative condition only when such flux reaches a predetermined maximum. 30
5. The combination with an electric circuit and a motor therein; of a motor-controller comprising a movable contact member, means adapted to retain the same normally in a predetermined position, and manually-operable means adapted to move said member to and retain the same in any other desired position, said latter means being controlled by the magnetic flux of such motor. 40
6. The combination with an electric circuit and a motor therein; of a motor-controller comprising a movable contact member, means adapted to retain the same normally in a predetermined position, and manually-operable means adapted to move said member to other positions, said latter means being rendered inoperative when the magnetic flux of such motor reaches a predetermined quantity. 50
7. The combination with an electric circuit and a motor therein; of a motor-controller comprising a movable contact member adapted to normally occupy its "off" position, a manually-operable member adapted to move said contact member to its "on" position, and retain said member in said position, said manually-operable member being rendered inoperative to retain said contact member in said "on" position when the magnetic flux of such motor reaches a predetermined quantity. 55
8. The combination with an electric circuit and a motor therein; of a motor-controller comprising a manually-operable member, a movable contact member, and means adapted to operatively connect said two members and controlled by the magnetic flux of such motor. 70
9. The combination with an electric circuit and a motor therein; of a motor-controller comprising a manually-operable member, a movable contact member, means for holding the latter normally in its "off" position, and means adapted to operatively connect said two members and actuated to disengage when the magnetic flux of such motor reaches a predetermined quantity. 80
10. The combination with an electric circuit and a motor therein, of a motor-controller comprising a movable handle, a member fixed thereto, a movable contact member adapted to normally occupy its "off" position, and means adapted to connect said two members and controlled by the magnetic flux of such motor. 85
11. The combination with an electric circuit, and a motor therein; of a motor-controller comprising a manually-operable member, a movable contact member adapted to normally occupy its "off" position, and means adapted to connect said two members whereby said contact member may be moved to other positions, said means being controlled by the magnetic flux of such motor. 95
12. The combination with an electric circuit and a motor therein; of a motor-controller comprising a movable handle, a member fixed to said handle, a contact member movable on said handle, means tending to retain said contact member in its "off" position, and means automatically operated to connect said contact member with said first-named member, whereby said contact member may be moved to its "on" position, said latter means being electrically controlled. 105
13. The combination of an electric circuit and a motor therein; a motor-controller comprising a movable contact member; means adapted to retain the same normally in its "off" position; and other means automatically operated to engage with said member, said latter means being manually operable to move said member to any other desired position and retain the same therein, said former means being rendered operative and said latter means inoperative only under the condition of an overload in the circuit. 115
14. The combination with an electric circuit and a motor therein; of a motor-controller comprising a manually-operable member, a movable contact member, and means carried by and movable with said manually-op- 125

erable member, and adapted to be automatically operated to connect the latter with said contact member, said means being operatively controlled independently of said manually-operable member.

15. The combination with an electric circuit and a motor therein; of a motor-controller comprising a manually-operable member, a movable contact member, means adapted to normally retain the latter in a predetermined position, and means carried by and movable with said manually-operable member, and adapted to be automatically operated to connect the latter with said contact member, both of said means being operatively controlled independently of said manually-operable member.

16. The combination with an electric circuit and a motor therein; of a motor-controller comprising a manually-operable member, a movable contact member, and means carried by and movable with said manually-operable member, and adapted to be automatically operated to connect the latter with said contact member, said means being electrically controlled.

17. The combination with an electric circuit and a motor therein; of a motor-controller comprising a manually-operable member, a movable contact member, means adapted to normally retain the latter in a predetermined position, and means carried by and movable with said manually-operable member, and adapted to be automatically operated to connect the latter with said contact member, said latter means being electrically controlled.

18. The combination with an electric circuit and a motor therein; of a motor-controller comprising a manually-operable member, a movable contact member, means adapted to normally retain said contact member in a predetermined position, and means carried by and movable with said manually-operable member, and adapted to be automatically operated to connect the latter with said contact member whereby the latter may be moved to other positions, said operative connection being broken to allow said first-mentioned means to become operative when a predetermined electrical condition is attained.

19. The combination with an electric circuit and a motor therein; of a motor-controller comprising a manually-operable member, a movable contact member, and movable means adapted to be automatically operated, under the condition of no load in the circuit, to connect said two members, and adapted to retain said connection except under the condition of an overload in the circuit, whereby said contact member may be moved in either direction, and retained in any desired position, said means being adapted to be elec-

trically operated to break the connection between said two members.

20. The combination with an electric circuit and a motor therein; of a motor-controller comprising a manually-operable member, a movable contact member adapted to normally occupy its "off" position, and movable means adapted to be automatically operated, when said contact member is in its "off" position, to connect said two members, whereby said contact member may be moved to and retained in its "on" position, said means being adapted to be electrically operated to break such connection between said two members.

21. The combination with an electric circuit and a motor therein; of a motor-controller comprising a manually-operable member, a movable contact member adapted to normally occupy its "off" position, and mechanically-operated means adapted to be automatically operated, when said contact member is in its "off" position, to connect said two members, whereby said contact member may be moved to and retained in its "on" position, said means being adapted, under the condition of an overload in the circuit, to be electrically operated to break such connection between said two members.

22. The combination with an electric circuit and a motor therein, of a motor-controller comprising a movable handle, a member fixed to said handle, a contact member movable on said handle, means adapted to be mechanically operated to connect said two members and to be electrically operated to break such connection.

23. The combination with an electric circuit and a motor therein, of a motor-controller comprising a movable handle, a member fixed to said handle, a contact member movable on said handle, means tending to hold said contact member in its "off" position and means adapted to be mechanically operated to connect said two members whereby said contact member may be moved to its "on" position, and to be electrically operated to break such connection.

24. The combination with an electric circuit and a motor therein, of a motor-controller comprising a manually-operable member, a movable contact member adapted to open and close said circuit and to cut out a resistance therein, means adapted to normally retain said contact member in a predetermined position, and means, controlled by the magnetic flux of said motor, mounted upon said first member and adapted to operatively connect said contact member with said first member.

25. The combination with an electric circuit and a motor therein, of a motor-controller comprising a manually-operable member, a movable contact member adapted to open

and close said circuit and to cut out a resistance therein, means adapted to normally retain said contact member in a predetermined position, and means, mounted on said first member, adapted normally to engage said contact member, whereby said contact member is operatively connected with said first member, and to be actuated to disengage said contact member when the magnetic flux of said motor reaches a predetermined quantity.

26. The combination with an electric circuit and a motor therein, of a motor-controller comprising a movable handle, a member fixed to such handle, a contact member movable on said handle, a spring adapted to normally retain said contact member in its "off" position, and a catch on said first-named member adapted normally to engage said contact member and to be disengaged therefrom when the magnetic flux of such motor reaches a predetermined quantity.

27. The combination with an electric circuit and a motor therein, of a motor-controller comprising a movable handle, a member fixed to such handle, a contact member movable on said handle, a spring adapted to normally retain said contact member in its "off" position, a catch on said first-named member adapted normally to engage said contact member, and a magnetizable member connected with a pole-piece of such motor and adapted when the magnetic flux in such pole-piece reaches a predetermined quantity to disengage said catch from said contact member.

28. The combination with an electric circuit and a motor therein; of a motor-controller comprising a manually-operable member, a movable contact member adapted to open and close said circuit and to cut out resistance therein, means adapted to normally retain said contact member in a predetermined position, and means automatically operated to connect said two members, said latter means being electrically controlled to be rendered inoperative only under the condition of an overload in the circuit.

29. The combination with an electric circuit and a motor therein; of a motor-controller comprising a manually-operable member, a movable contact member adapted to open and close said circuit and to cut out resistance therein, means adapted to normally retain said contact member in a predetermined position, and means inounted on said first member and adapted to be automatically operated to connect the latter with said contact member, said latter means being electrically controlled to be rendered inoperative only under the condition of an overload in the circuit.

30. The combination with an electric circuit and a motor therein; of a motor-controller comprising a movable handle, a member fixed to said handle, a contact member mov-

able on said handle, means tending to retain said contact member in its "off" position, means automatically operated to connect said contact member with said first-named member, said latter means being electrically controlled to be rendered inoperative only under the condition of an overload in the circuit, and a reversing-switch interlocked with said handle so as to be operable only when the latter is in its "off" position.

31. The combination with an electric circuit and a motor therein; of a controller member therefor, a retractile spring adapted to throw said member into its "off" position, a handle, and means for connecting the latter and said member, said connecting means rendering said spring inoperative, a predetermined quantity of flux in such motor rendering said connecting means inoperative and said spring operative.

32. The combination with an electric circuit and a motor therein; of a controller member therefor, a movable handle, a member fixed to the latter, a spring-actuated locking-piece secured to said fixed member and adapted to engage said controller member, and a retractile spring connected to the latter and adapted to actuate the same to assume its "off" position when said locking-piece is disengaged therefrom, the actuation of said locking-piece being controlled by the magnetic flux of the motor.

33. The combination with an electric circuit and a motor therein; of a movable controller member therefor, a handle, a spring-actuated catch carried by the latter and adapted to engage and disengage said controller member, a retractile spring arranged to throw the latter into its "off" position when said catch is disengaged, and a magnetizable member connected with a pole-piece of the motor-field, said catch being located in the magnetic field of said magnetizable member and forming an armature for the latter.

34. In devices of the general character described, the combination of a motor provided with a suitable casing; a controller comprising a movable contact member, manually-operable means adapted to move the latter "off" and "on" as desired, said latter means being inoperative only under the condition of an overload in the circuit, and means adapted to throw said contact member automatically to its "off" position under such overload; and a casing for said controller mounted upon said motor-casing.

35. In devices of the general character described, the combination of a motor provided with a suitable casing; a controller-casing mounted upon said motor-casing; a movable handle for holding and guiding the tool; a contact member within the latter normally operatively connected to said handle; and connecting means within said controller-casing for said handle and contact member

adapted to be actuated to release independently of the handle operation; and automatic means for throwing said contact member, when so released, to its "off" position, said contact member, when so released, being incapable of any manual operation or of any interference with its movement to its "off" position.

36. In devices of the general character described, the combination of a motor provided with a suitable casing; a controller-casing mounted upon said motor-casing; a movable handle for holding and guiding the tool extending exteriorly from within said controller-casing; a contact member within the latter normally operatively connected to said handle; and connecting means within said controller-casing for said handle and contact member adapted to be electrically actuated to release; and automatic means for throwing said contact member, when so released, to its "off" position, said contact member, when so released, being incapable of any manual operation or of any interference with its movement to its "off" position.

37. In devices of the general character described, the combination of a motor provided with a suitable casing; a controller-frame mounted upon said motor-casing substantially directly over a pole-piece of the motor-field; and a movable contact member mounted upon said controller-frame and controlled by the magnetic flux of the motor-field.

38. In devices of the general character described, the combination of a motor provided with a suitable casing; a controller-casing mounted upon said motor-casing substantially directly over a pole-piece of the motor-field; a movable handle for holding and guiding the tool extending exteriorly from within said controller-casing; a contact member within the latter; means tending to hold said contact member in its "off" position; and means normally operatively connecting said handle and said contact member, a predetermined quantity of magnetic flux in the motor-field actuating said latter means to disengage said contact member.

39. The combination with an electric circuit and a motor therein; of means for automatically breaking said circuit when the magnetic flux of the motor reaches a predetermined quantity.

40. The combination of an electric circuit and a motor therein; means for automatically breaking said circuit when the magnetic flux of the motor reaches a predetermined quantity; and manually-operable means for closing the break in said circuit made by said automatically-operating means.

Signed by me this 3d day of August, 1905.

ADOLPHI PEDERSEN.
